UNITED STATES PATENT OFFICE.

JOHNATHAN HAINES, OF CORONA, NEW YORK.

GASOLENE-SUPPLY APPARATUS.

1,188,446.

Specification of Letters Patent. Patented June 27, 1916.

Application filed April 22, 1915. Serial No. 23,268.

To all whom it may concern:

Be it known that I, JOHNATHAN HAINES, a citizen of the United States, and residing at Corona, in the county of Queens and State 5 of New York, have invented certain new and useful Improvements in Gasolene-Supply Apparatus, of which the following is a specification, such as will enable those skilled in the art to which it appertains to 10 make and use the same.

This invention relates to apparatus for supplying liquids of any kind or class for various purposes from a stationary or fixed reservoir or container and particularly to 15 apparatus of this class for supplying gasolene for use by motors and for other purposes; and the object thereof is to provide an improved apparatus of this class involving a main supply tank or container 20 which may be located in the basement of a building, or under a building, or under the pavement in front of a building, together with a supplemental tank or receiver which is preferably located in the pavement adja- 25 cent to a building and also adjacent to the curb, and which is supplied with gasolene from the main tank or container and from which the gasolene may be taken for use in or by an automobile or other power driven 30 vehicle, or for any desired purpose, said apparatus also involving other features of construction pertaining to the supply of the main tank or container with gasolene and the feeding thereof from said main tank or 35 container to the supplemental tank or receiver, so constructed and arranged as to render the apparatus most efficient in operation and use; and with this and other objects in view the invention consists of an 40 apparatus of the class specified, constructed and operating as hereinafter described and claimed.

The invention is fully disclosed in the following specification, of which the accompanying drawing forms a part, in which the separate parts of my improvement are designated by suitable reference characters in each of the views, and in which:—

Figure 1 is a sectional diagrammatic view 50 showing my improved apparatus complete and the method of assembling and operating the parts thereof; Fig. 2 a sectional detail view of the supplemental tank or receiver and showing the method of its use, the section being on an enlarged scale and on the line 2—2 of Fig. 3; Fig. 3 a view of the sup-

plemental tank or receiver similar to that shown in Fig. 1 but on an enlarged scale and showing the method of operating said supplemental tank or receiver; Fig. 4 a plan view of the supplemental tank or receiver and showing the same in inoperative position; and, Fig. 5 a section on the line 5—5 of Fig. 4.

In the practice of my invention, I provide 65 a main tank or container *a* which is inclosed in a concrete casing or structure *a*², and the tank or container *a* may be composed of sheet metal or any other suitable material. The tank or container *a* and its concrete 70 casing or structure *a*² is placed in a suitable pit or receiver *b* also composed of concrete or other suitable material, and in the bottom of which is a well *b*². The parts *a*² and *b* may be located at any suitable point in 75 the basement of a building, or under the sidewalk in front of a building, and preferably adjacent to the curb is a pit *b*³ composed of concrete or other suitable material adapted to receive a supplemental tank or 80 receiver *c* which may be lowered into the pit *b*³, or raised as shown in Figs. 1, 2 and 3.

The bottom of the main tank or container *a* is provided adjacent to one end thereof with a drain pipe *a*³ which is adapted to 85 discharge into the well *b*² and provided with a valve *a*⁴, and the top of the tank or container *a* is provided with a vent pipe *a*⁵ provided with a coupling head *a*⁶ below 90 which is a valve *a*⁷, and connected with the coupling head *a*⁶ are two supplemental vent pipes *a*⁸ and *a*⁹, and the vent pipe *a*⁵ extends downwardly into the bottom portion of the pit *b* and into the well *b*² and is 95 adapted to discharge into said well, while the vent pipe *a*⁹ is connected with another coupling *d* below the coupling *a*⁶, and said pipe *a*⁹ is provided at its lower end with a valve *d*², and connected with the pipe *a*⁹ above the valve *d*² is a vent pipe *d*³ which 100 leads into the pit *b*³, and the end of which is provided with a flexible tube *d*⁴ with which is connected a pipe *d*⁵ which passes up through the bottom of the supplemental tank or receiver *c* and approximately to the 105 top thereof when said tank or receiver is in an upright position as shown in Figs. 1, 2 and 3.

In the supplemental pit *b*³ is a vertically arranged intake pipe *e* having a valve *e*², 110 and with the lower end of which is connected a feed pipe *e*³ which extends into the ad-

5 jacent end of the pit b^3 and is connected with a supplemental vertically arranged inlet pipe e^4 which passes into the top of the main tank or container a , and is provided with a valve e^5 . The pipe e^4 is provided within the pit b^3 with a T-coupling e^6 with which is connected a flexible tube e^7 with which is connected a tube e^8 which passes through the bottom of and into the supplemental tank or 10 receiver c , and which is provided with a level gage e^9 , and with a valve f , and said tube e^8 is also provided with a discharge coupling or nozzle device f^2 with which may be connected a flexible hose or other device. 15 The inclosing walls of the pit b^3 , or the interior thereof, are provided with a lining g having an inwardly directed flange g^2 at the top thereof, and the supplemental tank or receiver c is mounted in a frame c^2 having 20 a back c^3 which forms a door for the pit b^3 , and is hinged to one end portion of the flange g^2 at g^3 , and with this construction the supplemental tank or receiver c may be raised into the vertical position shown in 25 Figs. 1, 2 and 3 whenever it is desired to take gasoline therefrom, and this gasoline is discharged through the nozzle or coupling device f^2 .

30 The front of the framework c^2 which carries the supplemental tank or receiver c is provided at the bottom thereof with laterally directed spring legs c^4 which when the frame c^2 is raised into an upright position move outwardly and the feet portions thereof enter 35 grooves c^5 in the side portions of the flange g^2 in the top of the pit b^3 , as clearly shown in Figs. 2 and 3, and hold the frame c^2 in an upright position, and when it is desired to lower said frame and the supplemental tank 40 or receiver into the pit b^3 , the legs c^4 are moved inwardly, and the door c^3 of the frame c^2 is provided with any suitable lock device c^6 , and a handle c^7 by which said door may be manipulated, or by which the frame 45 c^2 may be raised into an upright position and lowered into a horizontal position. The tank c is also provided in the bottom thereof with a cleaning or draining discharge nozzle c^8 , and one side of said tank is provided with 50 a gage c^9 by which the amount of gasoline therein may be determined.

55 Within the pit b is a yoke-shaped pipe h , one end of which is connected with the pipe a^3 at h^2 , and the other end of which extends out through one end of the pit b , as clearly shown at h^3 , and this pipe constitutes a water supply pipe, and the arm h^4 of said pipe is provided with a coupling h^5 with which is connected a vertical siphon tube h^6 which 60 extends downwardly into and approximately to the bottom of the main tank or container a .

65 The part h^4 of the pipe h is provided at h^7 with a valve device having a valve operated by a vertically movable stem h^8 with which

is connected a lever h^9 provided at its free end with a weight i with which is connected a wire i^2 which is passed around a pulley at i^3 and through the adjacent end of the pit b and into the pit b^3 , where it is passed around a pulley i^4 in the pit b^3 and up through the top portion of said pit and around another pulley i^5 supported at the back c^3 of the frame c^2 , and said wire is provided with a handle piece i^6 and a pull on said wire will raise the lever h^9 and operate the valve device h^7 and close said valve device and close the passage through the part h^4 of the yoke-shaped pipe h , and this operation of the lever h^9 will also open another valve device 70 j in the part h^4 of the yoke-shaped pipe h . The main tank or container a is provided at one end thereof with a gage k and the operation will be readily understood from the foregoing description when 75 taken in connection with the accompanying drawing and the following statement thereof.

In placing my improved gasoline supply apparatus in operation, a small amount of water is introduced into the main tank or 80 container a through the part h^8 of the yoke-shaped pipe h , and the pipe h^6 , and said tank or container is then filled with gasoline either through the pipe e^4 , or the pipe $e—e^3$. In order to fill the tank a through the pipe 85 $e—e^3$ the supplemental tank or receiver must be raised into the vertical position shown in Figs. 1, 2 and 3, and the extent to which said tank a is filled may be determined by the gage e^9 , or the gage k . 90

95 Whenever it is desired to fill the supplemental tank or receiver c the wire i^2 is pulled by means of the handle device i^6 and the lever h^9 is raised and the valve device h^7 is closed, and the valve device j opened which 100 operation admits water through the pipe member h^3 which water is discharged into the main tank or container through the siphon tube h^6 , and this water being under pressure the gasoline in the main tank or 105 container is forced into the supplemental tank or receiver c through the pipe e^3 and its connections e^7 and e^8 , and the valve device j is held open until the desired amount of gasoline has entered the supplemental 110 tank or receiver c , after which the valve f is closed and the wire i^2 and the pull device i^6 is released, and the lever h^9 drops into the position shown in Fig. 1, and the above 115 described operation ceases. The gasoline 120 may be taken from the tank c for any desired use by means of a flexible hose or similar device m connected with the coupling or discharge nozzle device f^2 and in order to control the supply and discharge of the gasoline to and from the supplemental tank or receiver c , said coupling or discharge nozzle device is provided with a valve m^2 . It 125 will be understood that in order to fill the supplemental tank or receiver it must be 130

raised into the upright position shown in Figs. 1, 2 and 3, and after the required amount of gasoline has been discharged from said tank or receiver, and it is desired to 5 lower the same into the pit b^3 as shown in Figs. 4 and 5, the gasoline still remaining in said tank or receiver is discharged therefrom into the tank by opening the valve f and in this operation a part of the water in 10 said tank a will be discharged therefrom through the siphon tube h^e .

It will be understood that as the gasoline is taken from the main tank or container a , said tank or container is gradually filled 15 with water, but when it is seen through the gages e^o or h^e that said tank or container is full of water, said water must be discharged and this may be done by opening the drain pipe a^s , or it may be done by introducing gasoline under pressure into the 20 tank a through either of the pipes e or e^4 .

In case the supplemental tank or receiver c should become flooded with gasoline in the filling of said tank, said gasoline will automatically 25 flow back through the pipe d^3 and a^s into the main tank or container, if the valve d^2 be open, and said supplemental tank or receiver c may be drained at any time through the bottom drain device c^s . It will 30 also be understood that the vent pipe a^s is necessary in apparatus of this class, and said vent pipe a^s and the pipe a^s operate as a discharge into the well b^2 of any overflow or 35 too great pressure of water in the main tank or container a . The pipe member a^s extends downwardly into the well b^2 and the part h^s of the yoke-shaped pipe h is above the part h^s of said pipe, and the pipe e^s is 40 slightly inclined downwardly in the direction of the main tank or container, and the pipe members h^s , h^s , e^s , e^s and the tank a form a siphon apparatus which insures the operation of the apparatus as herein described.

The well b^2 is provided with a sewer discharge pipe n and the well b^2 must always be filled, or approximately filled with water, and when this apparatus is used in a city or town where water hydrants or water supply connections may be made, the yoke-shaped pipe h , or the part h^s will serve as a connection to supply said water. If, however, the apparatus is used in the country the well b^2 may be filled by hand and a force 55 pump o may be employed, as indicated in dotted lines in Fig. 1, and said pump may be provided with a pipe o^2 which extends downwardly into the well b^2 , and in connection with the pump o a water tank o^s is 60 employed, and this tank is connected with the pipe member h^s by a pipe o^4 , and the tank o^s is provided with a vent pipe o^5 and the water will pass from the tank o^s through the pipe o^4 under sufficient pressure to operate 65 the apparatus as herein described.

In the foregoing description I have shown and described one form of my improved apparatus, but my invention is not limited to the details of construction herein shown and described, and various changes therein and 70 modifications thereof may be made, within the scope of the appended claims, without departing from the spirit of my invention or sacrificing its advantages, and it will also be understood that while I have described 75 my invention as an apparatus for supplying gasoline for distribution for various purposes, my invention is not limited to this use thereof and liquids of any kind or class may be similarly distributed or dispensed.

The opening in the top of the pit b^3 formed by raising the supplemental tank c may be closed temporarily, or while said supplemental tank is in its upright position, by any suitable plate or other device which may 80 be removed when it is desired to lower said supplemental tank or receiver within said pit, and while I have shown flexible coupling pipes d^4 and e^4 in the pit b^3 , my invention is not limited to devices of this 85 class, and what are known as compound stuffing boxes or couplings, or any other suitable devices of this class may be employed.

Having fully described my invention, 90 what I claim as new and desire to secure by Letters Patent, is:

1. In an apparatus of the class described, a main pit, a main tank or container located therein, a supplemental pit adjacent thereto 100 and a supplemental tank or receiver pivotally mounted in said supplemental pit and adapted to be raised into a vertical position, and hydraulically and manually controlled devices for filling the supplemental tank or 105 receiver from the main tank or container.

2. In an apparatus of the class described, a main pit, a main tank or container located therein, a supplemental pit arranged at a predetermined point in relation to the main 110 pit, a supplemental tank or receiver mounted in a frame pivoted in the supplemental pit, said frame being adapted to be raised into a vertical position above said pit and to be lowered into a horizontal position within 115 said pit and hydraulically and hand controlled devices for filling the supplemental tank or receiver from the main tank or container.

3. In an apparatus of the class described, 120 a pit, a frame hinged in said pit and adapted to be raised into a vertical position above said pit and to be lowered into a horizontal position within said pit, a tank or receiver mounted in said frame, and means for filling said tank or receiver and discharging the contents thereof.

4. In an apparatus of the class described, 125 a pit countersunk in a pavement adjacent to a building, and a tank or receiver within 130

said pit, said tank or receiver being adapted to be raised into a vertical position and to be lowered into a horizontal position.

5. In an apparatus of the class described, 5 a pit countersunk in a pavement adjacent to a building, and a tank or receiver within said pit, said tank or receiver being adapted to be raised into a vertical position and to be lowered into a horizontal position, and 10 means for filling said tank or receiver and for discharging the contents thereof at intervals.

6. In an apparatus of the class described, 15 a main tank or container, a supplemental tank or receiver mounted in a suitable frame, said frame being adapted to be raised into a vertical position and to be lowered into a horizontal position, means for filling the supplemental tank from the main tank, and 20 means for discharging the contents of the supplemental tank.

7. In an apparatus of the class described, 25 a main pit, a main tank or container located therein, a supplemental pit provided with a hinged door, a supplemental tank or receiver secured to said door within the pit, said door and tank being adapted to be raised into a vertical position, and means for supporting said tank and door in said position.

30 8. In an apparatus of the class described, a main pit, a main tank or container located therein, a supplemental pit provided with a hinged door, a supplemental tank or receiver secured to said door within the pit, said door 35 and tank being adapted to be raised into a vertical position, means for supporting said tank and door in said position, and means for filling said tank or receiver and for discharging the contents thereof at intervals.

40 9. In an apparatus of the class described, 45 a main pit, a main tank or container located therein, a supplemental pit provided with a hinged door, a supplemental tank or receiver secured to said door within the pit, said door and tank being adapted to be raised into a vertical position, means for supporting said tank and door in said position, means for filling said tank or receiver and for discharg-

ing the contents thereof at intervals, and 50 means for determining the amount of the contents discharged from said tank or receiver.

10. In an apparatus of the class described, a main pit, a main tank or container located 55 therein, a well located in said pit adjacent to and below said tank, a pipe forming a communication between said tank and well, said well being provided with a discharge pipe, a vent pipe communicating with the top of said tank and provided with supplemental vent pipes one of which communicates 60 with said well, a vertical siphon tube passed through said tank and communicating with the bottom thereof, a water supply pipe communicating with said siphon tube 65 and the supplemental vent pipe communicating with the well, valves placed in said water supply pipe, and an inlet pipe communicating with the top of said tank, a supplemental pit provided with a hinged door, 70 a supplemental tank or receiver secured to said door within the pit, said door and tank being adapted to be raised into a vertical position, and means for supporting said tank and door in said position, said tank or receiver being provided with a vent pipe which 75 passes upwardly therethrough and which is in communication with one of the said supplemental vent pipes by means of a flexible connection, and a supply pipe communicating with the bottom of said tank or receiver and placed in communication with the supply pipe of said main tank or container through a flexible connection, and means in 80 said supplemental pit and mounted on the door thereof for operating said valves in 85 said water supply pipe.

In testimony that I claim the foregoing as my invention I have signed my name in presence of the subscribing witnesses this 19th day of April, 1915.

JOHNATHAN HAINES.
